UNITED STATES PATENT OFFICE

2,432,974

CRADLE LOCK FOR CANNON WAGONS

Paul S. Stevens, Milwaukee, and Morton Sundnes,
South Milwaukee, Wis.

Application July 13, 1945, Serial No. 604,814

2 Claims. (Cl. 280—179)

1

This invention relates to means for securing artillery units and like heavy ordnance loads, upon transport wagons, and in its present embodiment is particularly adapted to use in the securement of the cannon unit on the cannon wagon shown in a co-pending application to Conlon et al., Serial No. 607,060, filed July 25, 1945, for Mobile heavy ordnance.

It has for an object to provide a simple rugged and effective means for holding a supporting leg of the cannon wagon of said co-pending application in proper interlocking relation whereby shifting of the load in any direction is prevented.

It is an especial object to provide means which will not require the location of a bolt immediately at either of the interlocking parts during loading and unloading operations. A further aim is to present a means for these purposes which will be self-contained and inseparable from the wagon, but readily available for movement to and from operative position manually, and being of such construction as to avoid impedance of loading and unloading operations, as well as avoiding possibility of misplacement of or damage to a screw fastening.

Additional objects, advantages, and features of the invention designed in novel construction, arrangement and combination of parts involved in the embodiment of the invention, as will be understood from the following description and accompanying drawings wherein:

Figure 1 is a fragmentary side elevation of the cannon wagon frame and cradle leg;

Figure 2 is a similar view showing the lock engaged with portions broken away;

Figure 3 is a top view showing the position of the parts as in Figure 2;

Figure 4 is a front end view in an engaged position, the disengaged position being indicated in dotted lines.

Referring more particularly to the drawings, there is illustrated a portion of the side member 152 of a cannon wagon frame, described in said aforementioned application Serial No. 607,060, which is of box girder form, on the top side of which there is fixed an anchor lug 230, having a recessed rearward side as at 10 extending transversely across the lug, the upper side of which slopes upwardly and rearwardly. This forms a rearwardly projecting bill 11 at the top of the lug. The leg 149 is formed with the foot block 149' at its rear side conforming to the shape of the recess 10 and adapted to fit snugly therein when the cannon unit is at the rear limit of its sliding movement on the wagon frame, the leg

2

serving as a sliding support which rests on the frame for supporting and guiding the cannon unit during loading and unloading operation, the members 152 at each side of the wagon frame then constituting a track-way upon which the cannon unit moves longitudinally on to or from the wagon. The rear side of the lug 230 is formed with a spherical socket 12 for a purpose which will be explained.

10 On the outer-face of the side member 152 adjacent the lug 230 there is mounted a bracket 13, consisting of an elongated flat base plate arranged longitudinally of the wagon secured flat against the side face of the member 152 and having at each end an outwardly projecting ear 14, one spaced a considerable distance rearwardly of the loaded position of the leg 149 and the other a short distance forwardly of the lug 230. A horizontal pivot pin 15 is set in these ears and has 15 pivoted and longitudinally slidable thereon a yoke member 16 which in operative position is U-shaped in plan, having a forward arm 17 adapted to extend over the side member 152 behind the base of the leg 149 at loaded position, and a forward arm 18 adapted to extend inwardly over the side member 152 in a corresponding position before the lug 230, being of somewhat greater dimension longitudinally of the wagon than the arm 17 and having engaged therethrough a binding screw 19 adapted to be projected rearwardly from the arm a distance and into the socket 12 so as to draw the yoke forwardly and clamp the leg 149 and its foot block 149' against the lug 230. The screw has a nut head 20 which is also apertured to receive a rod tool for turning thereof, and forwardly of the arm 18 a lock nut 21 is engaged upon the screw and against the rear side of the arm 18.

40 In planes with each of the arms 17 and 18 and at right angles to the latter, the yoke is provided with pivot ears 22 engaged revolvably and slidably around the pin 15 and of such length as to support the yoke so that its arms 17 and 18 may be swung through an arc of nearly 180° into position 45 over the top of the side member 152 and alternatively outwardly and downwardly as denoted in Figure 4, close beside the side member 152, and obviously well below the top of the wagon frame.

It should be noted that the opposed faces of 50 the arms 17 and 18 are spaced apart a distance substantially greater than the distance between the rearward face of the foot block 149' of the leg and the forward surface of the lug 230, so that with the screw 19 retracted forwardly within the arm 18, when the yoke is swung inward

over the wagon frame it is free for reciprocation a distance longitudinally of the wagon frame with respect to the lug 230, and the ear 14 is widely spaced rearwardly of the lug more than the thickness of the leg, permitting the front arm of the yoke to engage against the front side of the lug 230 in case of need.

In the use of this device, in unloaded condition, the screw 19 is fully retracted into the arm 18 and secured by the lock nut or otherwise so that loss is avoided and the space between the arms 17 and 18 fully cleared. The yoke may also hang free at the outer side of the wagon. Upon loading of the wagon, the cannon unit having been moved slidably on the frame from the distant rear end of the latter until the leg 149 is close to the lug 230 and nearly or quite in final engaged relation to the lug, the yoke 16 is swung upwardly and inwardly, being moved rearwardly on the pin 15 so that the arm 17 may clear the leg 149 in case the latter is not fully engaged with the lug 230. This brings the arms 17 and 18 over the top of the side member 152 with the screw 19 aligned with the recess 12 and rearward arm 17 behind the foot block of the leg. The lock nut 21 is now loosened and the screw 19 screwed inwardly so that its end engages in the recess 12 and draws the yoke 16 forwardly. Pressure of the arm 17 against the foot block 149 thereupon draws the latter forwardly into snug engagement in the recess 10 of the lug 230, the bill 11 then being engaged snugly over the foot block 149 and holding the load against possibility of relative vertical movement on the wagon frame as well as preventing its longitudinal movement in either direction. Lateral movement of the load is prevented by guide means 149" included on the leg and fitting within the side member 152 as described in said co-pending application. The lock nut 21 being tightened after the screw is in proper binding engagement with the lug 230, the lock is ready for travel.

For unloading the reverse operations of the parts are carried out, and will be understood without detailed description.

It will be understood that the construction and arrangement described and illustrated, while presenting the best embodiment of the invention

known to us, are purely exemplary, and various changes in the construction and arrangement, substitution of materials and equivalents may be made without departing from the scope of the invention set forth in the appended claims where-in we claim:

1. The combination of a transport frame having a trackway thereon, a load unit constructed to slide on said trackway, a combined anchor and stop member on said trackway, a supporting leg member attached to said load unit and slideable on said trackway, said leg member being so constructed and arranged for detachable interfitting engagement with the said anchor and stop member for holding said leg member against relative movement transverse to said trackway, a U-shaped yoke, means on the frame adjacent said anchor and stop member for mounting said U-shaped yoke for swinging and sliding movement whereby said yoke may be swung into operative position relative to said members to contain portions thereof; and means on said U-shaped yoke adapted to contact one of said members when said yoke is in said operative position for forcing said members together into interfitting engagement with each other.
2. The structure of claim 1 in which the means for mounting said yoke member comprises a pivot pin arranged longitudinally of the trackway and laterally of said anchor lug clear of the loading path of said unit and extended rearwardly of the locking position of said yoke the arms of said yoke being likewise spaced more than the distal faces of said leg and anchor lug when in loaded relation, said yoke being pivoted and slideable on said pin, and an extensible binding member on one arm of the yoke to engage the interposed parts when the yoke is in locking position.
